UNITED STATES PATENT OFFICE.

G. ADOLPH RIEDEL, OF PHILADELPHIA, PENNSYLVANIA.

IMPROVEMENT IN LOW-WATER INDICATORS FOR STEAM-BOILERS.

Specification forming part of Letters Patent No. 47,365, dated April 18, 1865.

To all whom it may concern:

Be it known that I, G. ADOLPH RIEDEL, of the city and county of Philadelphia, and State of Pennsylvania, have invented a new and Improved Self-Regulating Steam-Boiler and Steam Indicator and Alarm; and I do hereby declare that the following is a full, clear, and exact description of the construction and operation of the same, reference being had to the annexed drawings, making a part of this specification, in which—

Figure 1 is a side elevation of a steam-boiler with the improvements attached to the same. Fig. 2 is a top view of the same. Fig. 3 is an end view of the boiler and a portion of the frame-work with which it is connected. Fig. 4 is a horizontal section of a modified arrangement of the receiver C. Figs. 5 and 6 are a bottom and side view of the whistle O.

Like letters in all the figures represent the same parts.

The nature of my invention consists in so constructing and arranging the boiler and parts attached to the same that when the water in the boiler gets below the water-line the communication therewith is cut off from a water-receiver above it, where it had been forced by the pressure of steam in the boiler, and the water passes down a connecting-pipe by which the receiver is emptied and its position changed, by which a pump is set to work to fill the boiler, and a whistle or other device is operated to give an alarm; or else I connect with the boiler a weighted lever, or system of levers, which causes the boiler to ascend when the water is diminished to a certain degree, to produce the same results.

To enable others skilled in the art to make and use my invention, I will proceed to describe its construction and operation.

A is the boiler, which is supported by a suitable frame-work, B. It rests on the concaved edges of the plates B' B', which fit loosely in the grooved uprights of the frame B, to allow the boiler to be elevated in the manner I will hereinafter describe.

C is a receiver, which has communication with the boiler A by means of the shifting pipe D and the standing pipe E, the latter having a permanent connection with the boiler at its lower end, and a loose connection with the pipe D by means of the ball-and-socket joint a b. The upper end of the pipe C is

firmly secured to the lower side of the receiver C by means of screw-bolts which pass through the flange c of the pipe.

F is an air-vessel which connects with the said receiver. On the lower side of the receiver, at its rear end, there is an arm, G, which communicates with the lever H by means of the upright piece I. The lever works on the fulcrum-pin d in the standard J. There is an adjustable counter-weight, K, on the projecting end of the lever. The standard J has a socket in its upper end, in which the lower end of the bent rod L has an easy fit, to allow it to turn by the oscillation of the receiver, which will hereinafter be described. The other end of said rod is connected with the swivel M, whose front end fits on the stem e of the conical valve N of the whistle O, which is connected to the air-vessel F.

The construction and arrangement of the whistle and valve are clearly shown in Figs. 5 and 6.

The operation is as follows: When the water in the boiler is above the water-line, (indicated by the red line a b in Fig. 1,) to which the lower end of the standing pipe E projects, the pressure of the steam in the boiler causes the water to flow out of the boiler to the receiver C, except what is equivalent to the pressure of the air in the air-vessel F, at which time the receiver is brought into a horizontal position, (indicated by the red line c d;) but when the water in the boiler gets below the line a b, the communication being cut off from the pipe E, the water in the receiver, being specifically heavier than steam, passes down the pipe into the boiler, and the receiver being thus lightened the weighted lever H cauts the rear end upward, the ball-and-socket joint a b allowing it to move freely. The receiver is shown in its canted position in Fig. 1. In proceeding toward the position represented, the swivel M is turned partly round, which brings the opening f of the conical valve N in connection with the opening g of whistle O, which allows the steam to escape from the receiver C through the air-vessel F, and pass into the crown-recess h of the whistle, and give an alarm. The conical valve N, by means of the steam in the receiver C, is kept tight against its seat i, so as to prevent the escape of the steam at other times; but when the pressure of the steam in the boiler, and con-

squently in the receiver, is exhausted the valve N drops sufficiently to allow the atmosphere to flow into and occupy the receiver, and the water passing freely down into the boiler, all danger of freezing is prevented. I set a pump to work to fill the boiler by connecting one end of a rod or lever therewith, and the other end to the receiver C, or one of its attachments.

In Fig. 4 a modified arrangement is shown for connecting the receiver with the boiler. In this arrangement, which is represented by a longitudinal section through the receiver, P represents a pipe in the form of a T, having its small end screwed into the end of the receiver. In the large end of said pipe there is a valve, Q, of conical form, which fits a corresponding seat, j, in the pipe, leaving a chamber, k, between it and the plug or head l, which communicates with the receiver by means of the small end of the pipe. The hollow stem m of the valve fits in the horizontal part of the elbow R, which is connected at its lower end with the standing pipe E, hereinbefore described.

S is a helical spring on the stem m of the valve, which, bearing against the end of the elbow R and the contiguous end of the pipe P, keeps the valve Q at all times sufficiently tight against its seat to prevent the escape of the steam.

I contemplate using a flexible pipe as another modification of the connection of the receiver C with the boiler, the said pipe being simply connected at one end with the boiler in a similar manner to that of the standing pipe E, and the other end to the receiver.

In either connection of the receiver with the boiler a spring may be used for sustaining the weight of its rear end instead of the weighted lever H, although the lever in most cases may be found to be the most convenient device.

A modification of the invention is represented by a system of levers connected with the lower side of the boiler A. In this arrangement I dispense with the receiver C and produce the same results as those described by its change of position by the vertical rais-

ing of the boiler when the water is lowered therein to a given line.

In Fig. 1, T represents a lever whose fulcrum is situated in cheeks, between which the end of the lever works on the upper end of the standard U. V is a counter-weight on the lever. The said lever is connected to the levers T' and T'', which operate equally on each end of the boiler, by means of the jointed pieces 1 2 3. The levers T' and T'' have their fulcrums in the cheeks of the projections o o of the standing frame B, their outer ends bearing against the lower edges of the sliding plates B' B', on whose upper or curved edges the boiler at each end rests, as above described.

By the operation of the system of levers just described the boiler is elevated, when the weight of the water is reduced to a certain extent by falling to a given line, and the former, being connected with the pump and whistle by analogous means as those described above, adopted in the use of the receiver C, similar effects are produced by the elevation of the boiler as those accomplished by the canting of the receiver.

Having thus fully described my improved self-regulating steam-boiler and steam indicator and alarm, what I claim therein as new, and desire to secure by Letters Patent, is—

1. The oscillating receiver C, combined and arranged with the boiler A, substantially as described, and for the purposes specified.

2. The jointed pipes D and E, arranged and operating substantially as described.

3. The combination of the weighted lever H with the receiver C, substantially in the manner described, and for the purpose set forth.

4. The combination and arrangement of the conical valve N and whistle O, or other alarm, substantially as described.

In testimony that the above is my invention I have hereunto set my hand and affixed my seal this 24th day of January, 1865.

G. ADOLPH RIEDEL. [L. S.]
